Primary Examiner — Dana Meyrow(74) *Attorney, Agent, or Firm* — Porter Wright Morris & Authur, LLP(57) **CLAIM**

The ornamental design for a bottle, as shown and described.

DESCRIPTION

FIG. 1 is a perspective view of a bottle according to my new design;

FIG. 2 is front view thereof;

FIG. 3 is a rear view thereof;

FIG. 4 is a left side view thereof;

FIG. 5 is a right side view thereof;

FIG. 6 is a top view thereof;

FIG. 7 is bottom view thereof; and,

FIG. 8 is an enlarged fragmented view thereof, taken from FIG. 2.

The broken lines in the drawings illustrate the portions of the bottle that form no part of the claim.
